DRAWER LOCK

William C. Mayer, Jefferson, Wis.

Application September 30, 1942, Serial No. 460,256

1 Claim. (Cl. 45—94)

This invention appertains to furniture and more particularly to a novel drawer lock for file cabinets, desks and the like.

One of the primary objects of my invention is the provision of an automatic lock for tiers of drawers, in which the use of essential material, such as metal, is reduced to an extreme minimum, the main parts of the lock being formed from wood.

Another salient object of my invention is the provision of a novel anti-friction drawer lock in which the lock bar is positively moved both to its locking and unlocking position by the opening and closing of a single main drawer.

A further important object of my invention is the provision of a freely rotatable impeller roller arranged in rear of the drawer and actuated by the main or impeller drawer for positively raising and lowering the lock bar.

A still further object of my invention is the provision of a novel drawer lock of the above character, which will be durable and efficient in use, one that will be simple and easy to manufacture and one which can be incorporated in desks and file cabinets at a low cost.

With these and other minor objects in view the invention consists in the novel construction, arrangement and formation of parts, as will be hereinafter more specifically described, and illustrated in the accompanying drawings, in which drawings:

1. Figure 1 is a vertical sectional view through a file cabinet having my improved lock incorporated therewith, the section being taken on the line 1—1 of Figure 3.

Figure 2 is a view similar to Figure 1 but showing the top or impeller drawer moved to an open position for lowering the lock bar to permit the release of the bottom drawers.

Figure 3 is a horizontal sectional view through the cabinet taken on the line 3—3 of Figure 1 looking in the direction of the arrows.

Figure 4 is a transverse sectional view through the cabinet taken on the line 4—4 of Figure 1 looking in the direction of the arrows.

Referring to the drawings in detail, wherein similar reference characters designate corresponding parts throughout the several views, the letter C generally indicates a file cabinet and the same includes a top drawer 10 and a bottom drawer 11.

The cabinet C can be made in any preferred way as the construction of the cabinet itself forms no part of my present invention but it is to be noted that the same includes a top 12, side

walls 13 and a rear wall 14. A bottom frame 15 is provided in the cabinet and one or more intermediate frames 16 is also provided in the cabinet. The number of intermediate frames depends on the number of drawers in the cabinet.

The top or impeller drawer 10 can be provided with any preferred type of conventional key operated lock 17. The side walls 18 of the drawer 10 are extended beyond and rearwardly of the back wall 19 of this drawer to provide side plates 20. These side plates 20 are provided with inclined slots 21 which open out through the rear edges of the plates. As illustrated, the slots 21 incline upwardly and forwardly toward the drawer back 19.

While I have shown each drawer side 18 provided with the extension 20 it is to be understood, that if desired, the extension 20 can be provided only on one side of the drawer. The drawer 11 is provided with a latch hook 22.

Mounted for vertical sliding movement in the cabinet and in rear of the drawers is one or more lock bars 23. These lock bars are slidably mounted on the frames 15 and 16 and the frames 25 can be provided with headed pins 24 and the lock bars are provided with slots 25 for receiving said pins. Hence the lock bars are guided in their movement by the pins. The lock bar is provided with a keeper slot or socket 26 for engaging the keeper hook 22. As is clearly shown in Figures 1 and 2 the keeper slot 26 takes somewhat the form of a bayonet slot.

Extending transversely across the cabinet is a freely rotatable impeller roller 27. This roller is 35 rotatably mounted in openings 28 formed in the lock bars 23 and endwise movement of the roller 27 can be prevented by the use of suitable cotter pins 29 and washers 30. The ends of the impeller roller 27 are adapted to be received within 40 the inclined slots 21 as will be later more clearly set forth.

The lock bars 23, the impeller roller 27 and the side plates or extensions 20 are all formed of wood and if desired the guide pins also can 45 be formed of wood.

In the operation of my novel lock and referring more specifically to Figure 1, it will be noted that the drawers 10 and 11 are in their closed position and that the impeller roller 27 is disposed in the ends of the slots 21. Consequently the lock bars 23 are held in a raised position with the walls of the keeper slots in engagement with the latch hook 22. Consequently the opening of the lower drawer 11 is prevented.

Upon the unlocking of the top drawer 10, said

top drawer can be pulled outwardly as shown in Figure 2 and during this forward movement the impeller roller 27 will roll on the walls of the slots 21 and the walls of the slots, due to the inclination of the slots, will force the impeller roller downwardly and the impeller roller in turn will move the lock bars 23 downwardly. This will position the keeper slot 26 to permit the release of the keeper hook 22 and consequently the bottom drawer can be opened. When the bottom drawer is again closed and it is desired to lock the cabinet, the top or impeller drawer is moved to its closed position and the roller 27 will roll up the inclined walls of the slots 21 and the lock bars 23 will again be raised for moving the walls of the keeper slot 26 into locking engagement with the latch hook 22.

From the foregoing description, it can be seen that I have provided an exceptionally simple and durable form of drawer lock in which friction is reduced to a minimum.

Changes in details may be made without departing from the spirit or the scope of my invention, but what I claim as new is:

In an article of furniture, such as a file cabinet or desk, a frame, a control drawer slidably mounted in said frame, a drawer to be locked slidably mounted in said frame, vertically movable lock bars slidably supported by said frame arranged in rear of the drawer to be locked, said lock bars and said drawer to be locked having interengaging latching means, an impeller roller rotatably carried by the upper ends of the lock bars, and rearwardly extending plates on the control drawer having inclined slots for receiving said impeller roller for raising and lowering the lock bars upon opening and closing of the control drawer.

WILLIAM C. MAYER.
